UNITED STATES PATENT OFFICE.

FRANK BOWERS, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER CLEANER.

Application filed June 21, 1919. Serial No. 305,812.

The invention relates to boiler cleaners of that type particularly designed for use in connection with marine boilers where the cleaning is effected by reciprocatory blowers within the smoke box having jets directed against the flues. Heretofore, constructions of this type have been used in which the reciprocatory blower tubes are supplied with steam from a longitudinally movable header. This header in turn receives its steam from a stationary supply conduit and to permit of the movement, there is provided a flexible or swivel jointed connecting conduit between the supply conduit and the header. It is one of the objects of the invention to dispense with this flexible or swivel jointed connection, substituting therefor a simpler construction. The invention further consists in various features as hereinafter set forth.

In the drawings:

Figure 1 is a sectional elevation showing the blower as applied to a battery of marine boilers;

Figure 2 is an enlarged section of a portion of Figure 1.

A and A' are adjacent boilers in the battery. B and B' are the smoke boxes or breeching for conducting the products of combustion to the stack. C is a header extending transversely through each smoke-box and preferably continuously through the entire series. D are blower pipes connected with the header C and arranged in the various compartments of the smoke-box so as to extend parallel to the flue plate. The arrangement is such that when the header C is reciprocated longitudinally, the various blower tubes will traverse the series of tubes in their respective compartments directing jets of steam successively against the flues.

In place of the swivel jointed supply connection which has heretofore been used for furnishing steam to the header, I arrange either within or without the smoke-box parallel to the header a stationary header E. F are pipes telescopically engaging the header E at opposite ends thereof and laterally connected with the movable header C. As

all these pipes are parallel to each other, it 50 is obvious that the reciprocation of the header C will be permitted while maintaining the telescopic connection between the stationary header E and pipes F. Also due to the fact that the pipes F at opposite ends of 55 the stationary header are of equal cross-sectional area, the pressure of steam will be balanced. Thus, after the steam is supplied for the stationary header E, it will be continuously conducted to the movable header C and the reciprocatory movement of the latter will be permitted without resistance from the steam.

For reciprocating the cleaners I preferably provide mechanism for the whole battery of boilers. This consists of a chain or other actuating connection G which is connected by reason of the plugs K to the opposite ends of the continuous header C and after passing over shoes or pulleys H is centrally connected with an actuating mechanism I. It is, of course, understood that the header is plugged or closed, as indicated at K, so as to avoid discharge of steam therethrough.

What I claim as my invention is:

1. In a boiler cleaner, the combination with a longitudinally reciprocatory header, of a stationary header arranged parallel thereto and connected with a source of supply of steam, and a pair of conduits telescopically engaging said stationary header at opposite ends thereof and laterally connected to said reciprocatory header, thereby forming a balanced connection.

2. In a boiler cleaner, the combination with a reciprocatory header, of a stationary header extending in the direction of reciprocation of the first mentioned header, and a pair of conduits oppositely telescopically engaging said stationary header and respectively connecting with the end portions of the reciprocatory header to establish a balanced fluid supply thereto in all positions of reciprocation thereof.

In testimony whereof I affix my signature.

FRANK BOWERS.
